UNITED STATES PATENT OFFICE.

CLARK E. CLAPP, OF ST. JOSEPH, MISSOURI, ASSIGNEE OF ONE-HALF TO RALPH L. GREEN AND WILLIAM I. GREEN, OF ST. JOSEPH, MISSOURI.

TRAIN-STOPPING APPARATUS.

1,142,492.

Specification of Letters Patent. Patented June 8, 1915.

Application filed July 7, 1914. Serial No. 949,451.

To all whom it may concern:

Be it known that I, CLARK E. CLAPP, a citizen of the United States, residing at St. Joseph, in the county of Buchanan and State 5 of Missouri, have invented new and useful Improvements in Train-Stopping Apparatus, of which the following is a specification.

This invention relates to improvements in 10 train stopping apparatus and has particular application to fluid operated apparatus of this character.

In carrying out the present invention, it 15 is my purpose to provide apparatus of the class described which will embody fluid motors connected with the throttle valve lever and the engineer's brake valve handle respectively and adapted to have communication with a source of supply and a valve 20 controlling communication between the motors and the source and designed to be actuated to open position in the event of the train running by a danger signal thereby establishing communication between the 25 source of supply and the motors and effecting the operation of the brake valve to reduce the train line air pressure and the closing of the throttle valve to cut off the flow of steam to the drive cylinders of the locomotive, means being provided to restore the 30 valve to normal closed position succeeding the operation of the motors.

It is also my purpose to provide apparatus of the type set forth which will 35 embrace the desired features of simplicity, efficiency and durability, which may be installed and maintained at a minimum expense and which will operate effectively under all conditions.

With the above and other objects in view, 40 the invention consists in the construction, combination and arrangement of parts hereinafter set forth in and falling within the scope of the claims.

In the accompanying drawings; Figure 1 is a transverse sectional view through a trackway and locomotive thereon showing my invention installed. Fig. 2 is a diagrammatic view of the car carried mechanism. Fig. 3 is a longitudinal sectional view 45 through the motor for operating the throttle valve. Fig. 4 is a vertical sectional view through the controlling valve showing the connections between such valve and the operating rod and restoring motor. Fig. 5 is

a longitudinal sectional view through the motor for operating the engineer's brake valve.

Referring now to the drawings in detail, 50 1 designates a steam driven locomotive designed to traverse the trackway 2. In the present instance, the trackway 2 is divided into blocks and located at the entrance to each block is a semaphore 3, while disposed adjacent to one line of rails of the trackway 55 at the entrance to each block is a shoe 4 mounted in suitable bearings and connected through the medium of link mechanism 5 with the signal blade of the adjacent semaphore so that when the signal blade is moved 60 to danger position the shoe will be elevated or rendered active and rendered inactive or lowered when the blade denotes clear.

6 and 7 designate respectively the throttle valve lever and engineer's brake valve of a 65 steam driven locomotive and adjacent to the throttle valve lever and the handle of the engineer's brake valve are fluid operated motors each comprising, in the present instance, a cylinder 8 and a piston 9 disposed within the cylinder and capable of sliding movement therein and provided with a piston rod 10 projecting outwardly of one end of the cylinder. The outer end of the piston rod 10 of the motor adjacent to the throttle valve lever is suitably connected with such lever, while the outer end of the piston rod 70 of the motor adjacent to the brake valve is appropriately connected with the handle of such valve so that when the pistons of the 75 motors are actuated under fluid pressure, the throttle valve lever will be first unlocked or relieved of the influence of the dog and then swung to close the throttle valve, and the engineer's brake valve actuated to effect 80 the application of the brakes to the wheels.

The main air reservoir of the air brake system of the train is indicated at 11 and leading from such reservoir is a pipe 12 having the terminal thereof connected with the outer end of the cylinder 8 of the motor for operating the throttle valve lever and connected with the pipe 12 is a branch pipe 13 leading into one end of the cylinder 8 of the motor for actuating the engineer's brake 85 valve.

Connected in the pipe 12 between the main air reservoir 11 and the motors and controlling communication between such reservoir and motors is a controlling valve 14. 90

In the present instance, this controlling valve comprises a cylindrical casing 21 having the upper end portion 22 thereof of relatively large diameter.

- 5 Formed in the side walls of the casing 21 at the small end portion thereof at diametrically opposite points are alining openings establishing communication between the interior of the casing and the pipe 12, while
- 10 formed in the upper end wall of the relatively large end portion 22 of the casing is a port connected by way of a pipe 23 with the side wall of the cylinder 8 of the throttle valve lever actuating the motor adjacent
- 15 to the rear end of such cylinder, communication between the cylinder and the pipe 23 being controlled by the piston in such cylinder, such piston placing the cylinder in communication with the pipe when the same has
- 20 reached the limit of its movement within the cylinder.

Slidably mounted within the lower end portion of the casing 21 and normally across the openings establishing communication between the casing and the pipe 12 is a sliding valve 24 and connected with the upper face of the valve 24 and disposed within the relatively large end portion 22 of the casing is a piston head 25.

- 25 Connected with the lower face of the valve 24 and projecting through the bottom end wall of the casing 21 is a stem 26 having the lower end thereof disposed in the path of movement of a lug 27 formed on the upper end of a vertical actuating rod 28 mounted for sliding movement within alining bearings carried by the locomotive.

Encircling the rod 28 is a tension spring 29 having one end fastened to the rod and 40 the opposite end secured to one of the bearings of the latter, such spring acting to hold the lug 27 normally in a position to engage the stem 26 in the upward movement of the rod 28. The lower end of the rod 28 is preferably forked and journaled in the forked end thereof is a roller 20 adapted to ride upon the shoe 4 when the latter is in active or elevated position to slide the rod 28 upwardly.

- 45 By means of this construction, it will be seen that when a signal is set at danger the adjacent shoe will be elevated or rendered active and should a train run by the signal the roller 20 will ride upon the shoe 4 thereby elevating the rod 28 and engaging the lug 27 with the stem 26 of the valve 24 to carry the latter upwardly within the casing 21 and so establish communication between the main air reservoir 11 and the cylinders 8 of 55 the motors, air passing from the reservoir 11 through the pipe 12 and into the cylinders of the motors controlling the throttle valve lever and engineer's brake valve whereby the throttle valve is closed and 60 the brake valve operated to cause a

reduction in the train line air pipe whereby the brakes will be applied. Immediately that the piston within the cylinder 8 of the motor actuating the throttle valve lever reaches the limit of its path of movement under the action of the air from the main air reservoir, the port in said cylinder connected with the pipe 23 is uncovered so that communication is established between the cylinder 8 and the relatively large end portion 22 of the casing 21 and as the area of the piston head 25 is greater than the lower surface of the sliding valve 24, the pressure of the air on the piston head overcomes the pressure on the under side of the valve and slides the latter to normal closed position, thereby cutting off communication between the main air reservoir 11 and the motors so that the engineer may regain control of the train. 85

The cylinders 8 are preferably provided with vent cocks so that the same may be vented to release the air pressure therein succeeding the closing of the controlling valves, thereby enabling the engineer to regain control of the throttle valve and the brake system with ease. 90

When it is desired to relieve the stem 26 of the influence of the rod 28, as when double heading, or connecting an engine with each end of a train, the rod 28 is rotated within its bearings against the action of the springs 29 so that the lug 27 is moved to one side of the valve stem 26, a handle 30 being connected to the actuating rod 28 adjacent to the lug 27 whereby such rod may be rotated.

I claim:

1. In automatic train stopping apparatus, the combination with a fluid motor including a cylinder, a piston therein and a source of supply for said motor, a connection between said source of supply and motor, of a valve comprising a cylinder casing having a small diameter and a relatively large diameter, the wall of the small diameter being formed with ports at diametrically opposite points establishing communication between said connection and casing, a valve in the small end of said cylinder and capable of sliding movement therein and normally covering said ports, a piston in the relatively large end of said casing, a connection between said piston and valve, a connection between the cylinder in said motor and the large end of said casing controlled by the piston in said cylinder whereby communication between the fluid end of the motor cylinder and the large end of said casing will be established succeeding the movement of the piston under the action of the fluid, and means for moving said valve to open position whereby communication will be established between said source and motor and communication established between the fluid end of said 115

cylinder and the large end of said casing succeeding the movement of the piston so that the fluid will flow from the cylinder into the large end of said casing to actuate the piston therein to restore the valve to normal position.

2. In automatic train stopping apparatus, the combination with a fluid motor including a cylinder, a piston therein and a source of supply for said motor, a connection between said source of supply and motor, of a valve comprising a cylinder casing having a small diameter and a relatively large diameter, the wall of the small diameter being formed with ports at diametrically opposite points establishing communication between said connection and casing, a valve in the small end of said cylinder and capable of sliding movement therein and normally covering said ports, a piston in the relatively large end of said casing, a connection between said piston and valve, a connection between the cylinder in said motor and the large end of said casing controlled by the piston in said cylinder whereby communication between the fluid end of the motor cylinder and the large end of said casing will be established succeeding the movement of

the piston under the action of the fluid, means for moving said valve to open position whereby communication will be established between said source and motor and communication established between the fluid end of said cylinder and the large end of said casing succeeding the movement of the piston so that the fluid will flow from the cylinder into the large end of said casing to actuate the piston therein to restore the valve to normal position, a stem connected to said valve and projecting through one end wall of said casing, a vertical actuating rod capable of sliding movement, a lug on said rod adapted to engage said stem to actuate the valve, means for swinging said rod to move said lug out of engagement with said stem, and a spring surrounding said rod for restoring the latter to normal position succeeding the release of said last-named means.

In testimony whereof I affix my signature in presence of two witnesses.

CLARK E. CLAPP.
